UNITED STATES PATENT OFFICE.

GEORGE W. FOSTER, OF PROVIDENCE, RHODE ISLAND, ASSIGNOR TO UNIVERSAL WINDING COMPANY, OF BOSTON, MASSACHUSETTS, A CORPORATION OF MASSACHUSETTS.

BOBBIN-MAGAZINE.

1,218,601.

Specification of Letters Patent.

Patented Mar. 6, 1917.

Application filed December 18, 1915. Serial No. 67,623.

To all whom it may concern:

Be it known that I, GEORGE W. FOSTER, a citizen of the United States, residing at Providence, in the county of Providence, 5 State of Rhode Island, have invented certain new and useful Improvements in Bobbin-Magazines, of which the following is a specification.

My invention is an improved creel or supply-magazine for use in delivering yarn, thread or the like to winding machines and other textile apparatus. The object of my improvement is to provide means for supporting a plurality of cops or bobbins in series with their ends tied or spliced together and held under tension so that the yard will unwind continuously from one bobbin to another without interruption in its delivery until the whole supply is exhausted. To this end my invention consists essentially of a device for mounting the bobbins in series with their delivery-ends arranged in alinement with guiding-means over which the last-delivering end of the yarn from one 25 bobbin draws to the leading end of the next bobbin, to which it is spliced, and with means for holding the spliced ends under tension to prevent them from becoming entangled and to provide for an unrestricted, 30 uninterrupted delivery from one bobbin to another throughout the whole series. In this way my improved magazine furnishes a continuous supply of yarn from a series of bobbins for delivery to a winding or other 35 machine without requiring stopping the operation of the machine to piece up the ends. My improved device provides for important economies in the operation of the machine to which it is applied, thus increasing its 40 production while also improving the character of its product as more fully set forth hereinafter.

The manner and means for carrying out these improvements are fully described in 45 the following specification, illustrated by the accompanying drawings, in which like reference characters designate like parts. In the drawings:—

Figure 1 is an elevation of a usual style 50 of winding machine showing my improved bobbin-magazine applied to use in connection therewith;

Fig. 2, an enlarged, front elevation of the magazine, showing the manner of applying 55 the bobbins thereto and illustrating the man-

ner of connecting their ends and threading them up;

Fig. 3, a side view of the same;

Fig. 4, an end view; and

Fig. 5, a view in detail of the tension-device or end-holding-means for the spliced 60 yarns.

Referring first to Fig. 2, my improved bobbin-magazine or creel may be made of any appropriate shape, but as here shown takes the form of a rectangular frame F preferably constructed of wood, sheet-metal or other light material. For the sake of convenience in describing it, the end f of the frame F may be considered its base, f' its 65 top and f² and f³ its sides, although in practice the magazine may be set in other positions than that here shown, for instance, with the side f² serving as its base. Along the inside of the upright f² is a series of bobbin-holders H, H, etc., for supporting the cops or bobbins B in parallel alinement. The holders H may be of any preferred form as usually employed for similar purposes, but as here shown consist simply of wooden 70 plugs having pins h fastened in holes in the side f², and formed with conical portions h' adapted to fit tightly within the tapered bores of the wooden bobbins b on which the 75 yarn is wound. In some instances where a 80 different form of supply-bobbin is to be used, such as a cop wound on a paper tube, the holder H might take the form of a dead spindle or, if preferred, an expansible 85 spring-catch, or an outer spring-clip such as 90 used on shuttles could be employed. With the present arrangement the bobbin b is merely forced onto the tapered holder H with a wedging fit to hold it in place with its nose or delivery-end pointing toward 95 the side f³.

Referring to Fig. 3, the side f³ of the frame F is constructed with two parallel strips f⁴, f⁴ spaced slightly apart and fastened by screws, nails or other means to the ends of the base f and top f'. Extending between the strips f⁴, f⁴ are the yarn-guides g, g, etc., arranged in series and spaced to bring them in alinement with the axes of the bobbins B when the latter are placed on their holders 100 H. The guides g, g, may conveniently be constructed in the form of round, metal pins having their ends inserted in transverse holes in the strips f⁴, f⁴. Any other suitable 105 guide such as a porcelain rod or looped wire 110

might be used in place of the pins g , but this detail is not important.

Secured to the side of the upright f^2 and spaced between the centers of the bobbin-holders H are the tension-devices or end-holding clips C also arranged in series and corresponding in number to the number of bobbins used in the magazine. As illustrated in detail in Fig. 5 the clips C consist simply of two overlying, flat pieces c, c of spring-metal, held together and fastened in place by the screws c' . The ends of the pieces c, c are preferably spread apart or curved outwardly at the top to provide a flaring entrance for the yarn to facilitate the operation of drawing it into place to be clamped between the sides of the clip.

Referring to Fig. 4, the end of the top piece f' is cut away at f^5 and a wire pigtail P of usual form is driven into the wood to secure it in place with its eye p in alinement with the yarn-guiding pins g, g , etc. Fas-
20 tened to the side of the upright f^2 , see Figs. 1 and 2, is a pair of clamping-fingers D, D preferably constructed of spring-metal and shaped to adapt them to be sprung around a rod or other support on the machine to which the magazine is attached. The method of applying the device to use is as
30 follows:

Referring to Fig. 2, the frame F is set in any convenient position and the full bobbins B are fitted snugly to their holders H . The leading or delivery end y of the yarn on the first bobbin 1 is then drawn up over the first guiding-pin g in the series and thence led through the eye p of the pigtail P . The opposite or last-delivering end y' of the yarn on this bobbin is next tied or spliced to the leading end y^2 of the next bobbin 2 after this end has first been drawn up over the second guiding-pin g of the series. After these two ends of the yarn from the adjacent bobbins 1 and 2 have been tied together as shown at
45 x in Fig. 2 the end y' is drawn down into the tension-clip C to hold it taut where it leads from the base of the bobbin 1, while the end y^2 leading from the nose of the bobbin 2 is left relatively slack. It will be understood
50 that when the yarn is spun or wound on its wooden support or bobbin b the first-wound and last-delivering end y' is left free to provide for its subsequent splicing to the leading end y^2 of the next bobbin in the series.
55 That is to say, in the process of spinning or winding the yarn on its support a free length of yarn y' is measured off at the start and this is usually coiled loosely around the butt of the bobbin b to hold it in reserve and prevent it from being snarled or broken. When the bobbins are placed in the magazine the ends y' are simply pulled off or uncoiled to provide the free length for tying up to the delivery-end of the next bobbin. In this
65 manner the last end of the yarn from each

bobbin in the series is spliced to the first or leading end of the next bobbin as shown in Fig. 2. The connected ends of all the bobbins are then drawn into the tension-clips C and this last provision for holding the ends 70 taut is most important as otherwise the yarn will not deliver freely but is apt to snarl and kink resulting in broken ends which interrupt the delivery. That is to say, it has been found that unless the yarn is held relatively 75 taut where it leads from the base of one bobbin to the nose of the next bobbin the last end will not unwind freely but is liable to kink and snarl or to catch on the butt of the bobbin causing it to be broken.

Usually the bobbins are applied to the magazine and their ends spliced together by one or more operators who do this work alone. This tends toward greater care and more expert attention in the tying of the 85 knots and results in better and more uniform work. After the magazines have been supplied with the bobbins and the ends have been properly tied up and positioned as above described the frames F are taken to 90 the machine to which the yarn is to be supplied. In applying the magazines to the machines they may be arranged in any convenient manner by placing them in racks, setting them on the floor or attaching them to 95 supports overhead. In Fig. 1, I have illustrated the preferred manner of their use in connection with a well known type of cone-winding machine. These machines are usually arranged with a series of heads W 100 mounted on a horizontal bed K supported on legs L . Connecting the legs L is a horizontal tie-rod R which forms a convenient support for the frame F . The magazine is set with its base end f on the floor and then 105 tilted back to clasp the spring clamping-fingers D, D around the rod R . When the magazine is held in this position the pigtail P will be in alinement with the tension-device T on the winding-head W so that the 110 end y of the yarn may be drawn up and threaded therethrough, whence it leads to the winding-spindle S . It will be understood that there are a plurality of heads W on the bed K , each with a separate spindle S overhanging its front. In applying the magazines to the machine it has been found convenient to set a considerable number of them in place under the several spindles S , as many as can be accommodated in the space 115 between the legs L . In this way the operator of the machine is always provided with an ample supply of full bobbins so that when one magazine is run out or exhausted another one may be slid into place. The bobbin-tender who distributes the magazines has simply to remove the exhausted ones and replace them with full ones and in this way the machine is kept continuously supplied and the operator is relieved of the work of 120 125 130

placing the bobbins and tying up the ends. In other words, the machine operator has only to operate the machines and to piece up once for each winding as next explained.

- 5 With a supply of filled magazines in place under the machine the operator simply slides the nearest one into position below the appropriate tension-device T so that the pigtail P will align therewith.
- 10 The yarn y is then drawn up through the tension-device T and its end secured to the winding-spindle S. The operator has then merely to start the machine and the yarn will be wound onto the spindle S continuously from the whole series of bobbins B in the magazine F. That is to say, the yarn y will first unwind from the upper bobbin 1 and when this is exhausted its last-delivery end y' will be drawn out from
- 15 the tension-clip C and the slack extending between the first bobbin and the second one will be taken up, after which the bobbin 2 will begin to deliver. After the yarn is exhausted from bobbin 2, the slack held
- 20 in the next tension-clip C is again taken up and bobbin 3 commences to deliver and so on down through the last bobbin in the series.

It is to be noted that as the yarn delivers from each bobbin in the series it draws around the appropriate guiding-pin g and then straight up through the pigtail P. In this way a constant tension is maintained on the delivering yarn from the first bobbin down to the last one in the magazine. Furthermore, as the yarn delivers from the lower bobbins it draws up past the series of pins g and is thereby prevented from excessive ballooning so that no serious fluctuations in the resistance to its delivery can occur from this cause.

Usually a sufficient number of bobbins is placed in the magazine F to supply enough yarn for one full cone or package Y wound on the spindle S, so that the winding is made continuous without stopping the machine from start to finish of the package. After the package is completed it is removed from the machine, another magazine F is slid into place, the yarn therefrom threaded up to the spindle S as before described and the winding started once more. The machine is usually arranged to stop automatically when the package attains the required size so that the operator needs only to give his attention at the commencement of the winding. It will thus be seen that the operator is relieved of all the work of supplying new bobbins each time the yarn is exhausted from the one delivering because the delivery is made continuous from start to finish of each package. In some instances when it is desired to wind packages of a specified weight or containing a certain predetermined yardage of material

the yarn wound onto the supply-bobbins may be first weighed or measured accordingly. The winding machine will stop automatically when the supply runs out and in this way all packages may be wound of uniform size or weight without attention on the part of the operator as to this detail.

It will be seen from the above that my improved magazine provides a more convenient and economical method of supplying yarn to winding or other textile machines. Through its use the operator is relieved of the work of placing the individual bobbins and piecing up the ends and is therefore free to give his whole time to the manipulation of the machine itself. This naturally results in allowing the operator to tend a greater number of machines, thereby increasing the production both per spindle and per operator while also improving the quality of the product. Where the operator has only to look after the machine itself it is obvious that better and more expert attention can be given thereto. Furthermore, where the piecing up of the bobbins is performed by one or more operators particularly skilled in this work the knots will be tied more evenly and uniformly resulting in an improved quality of the fabric in which the yarn is ultimately used.

Various modifications might be made in the structure and arrangement of my improved device without departing from the spirit or scope of the invention; therefore, without limiting myself to the exact embodiment shown and described, what I claim is:

1. In a supply-magazine for textile machines, the combination with means for supporting a plurality of bobbins arranged with their ends connected together in series to adapt the yarn to deliver continuously therefrom, of guiding-means for directing the last-delivering end from one bobbin to the first-delivering end of the next bobbin, and means for yieldingly holding the ends under tension where they lead from one bobbin to another throughout the series.

2. In a supply-magazine for textile machines, the combination with means for supporting a plurality of bobbins arranged with their ends connected together in series to adapt the yarn to deliver continuously therefrom, of a series of guiding-pins arranged in alinement with the axes of the individual bobbins to direct the last delivering end from one bobbin to the first-delivering end of the next bobbin, and means for yieldingly holding the ends under tension where they lead from one bobbin to another.

3. In a supply-magazine for textile machines, the combination with means for supporting a plurality of bobbins arranged

41
 with their ends connected together in series to adapt the yarn to deliver continuously therefrom, of means for guiding the last-delivering end from one bobbin to the first-delivering end of the next bobbin throughout the series, and spring-clips adapted to seize the ends leading between the bobbins to hold them under tension until the yarn starts to deliver from one bobbin to the next bobbin of the series.

4. In a supply-magazine for textile machines, the combination with a plurality of holders arranged to support a series of bobbins having their ends connected to adapt the yarn to unwind continuously therefrom, of a series of yarn-guides positioned in alinement with the holders to direct the yarn from the base of one bobbin to the nose of the next bobbin in the series, and a series of yarn-holding devices arranged adjacent the bobbin-holders and adapted to yieldingly hold the ends leading from the bases of the bobbins to prevent them from snarling or catching as the yarn draws from one bobbin to another.

5. In a supply-magazine for textile machines, the combination with a frame-like support, of a plurality of bobbin-holders spaced in parallel alinement along one side of the frame to support a series of bobbins arranged with their ends connected to adapt the yarn to deliver continuously from one bobbin to another, a series of yarn-guides on the opposite side of the frame positioned in spaced alinement with the bobbin-holders to direct the yarn from the base of one bob-

bin to the nose of the next bobbin, and a series of yarn-receiving clips spaced along the side of the frame on which the individual bobbin-holders are supported to hold the ends of the yarn leading from the bases of the bobbins to prevent them from snarling or catching as the yarn draws from one bobbin to another.

6. In a supply-magazine for textile machines, the combination with a rectangular frame, of a plurality of bobbin-holders mounted on the inside of the frame to support a series of bobbins arranged with their ends connected together to adapt the yarn to deliver continuously therefrom, a series of yarn-guiding pins secured in parallel spaced relation on the opposite side of the frame to direct the yarn from the base of one bobbin to the nose of the next bobbin, guiding-means at one end of the frame positioned in alinement with the guiding-pins to lead the yarn away from the frame as it draws across any one of the guiding-pins, and a series of spring-clips spaced along the side of the frame adjacent the bobbin-holders and adapted for yieldingly holding the spliced ends of the bobbins under tension to prevent the yarn from tangling as it delivers from one bobbin to another.

65
 In testimony whereof I affix my signature in presence of two witnesses.

GEORGE W. FOSTER.
